UNITED STATES PATENT OFFICE.

GEORGE W. FLOOD, OF CLAY BANK, MICHIGAN, ASSIGNOR OF ONE-HALF
TO JOHN F. KELLEY, OF SAME PLACE.

CHURN-MOTOR.

SPECIFICATION forming part of Letters Patent No. 245,148, dated August 2, 1881.

Application filed May 18, 1881. (Model.)

To all whom it may concern:

Be it known that I, GEORGE W. FLOOD, of Clay Bank, in the county of Oceana and State of Michigan, have invented certain new and useful Improvements in Churn-Motors; and I do hereby declare that the following is a full, clear, and exact description of the invention, which will enable others skilled in the art to which it appertains to make and use the same, reference being had to the accompanying drawings, which form a part of this specification.

Figure 1 is a front view of my improved churn-operating device. Fig. 2 is a side view of the same. Fig. 3 is a vertical cross-section; 15 and Fig. 4 is a horizontal sectional view on the line *x x*.

Corresponding parts in the several figures are denoted by like letters of reference.

This invention relates to machines or devices for operating that class of churning having vertical reciprocating dashers; and it consists in certain improvements in the construction of the same, which will be hereinafter fully described, and particularly pointed out in the 25 claim.

In the drawings hereto annexed, A represents a rectangular base-frame having suitably-braced uprights B B connected by a top piece, C, and by suitable transverse braces, D 30 E. The ends of the two latter are connected by the vertical guides F F, forming bearings for the U-shaped shoes G, which are pivoted upon spindles H extending from the sides of the head I, to which the dasher-stem is connected, as will be hereinafter described.

The inner sides of the side pieces, J J, of base-frame A are provided with longitudinal grooves K K, to accommodate a sliding floor or platform, L, upon which the churn-body M is 40 supported, said platform being preferably provided with a recess, N, to receive and hold the churn-body. The latter consists preferably of an ordinary earthen crock or vessel, which is cleaner and, in many other respects, better than a wooden churn. To hold the said 45 churn-body securely in place during operation I employ a pair of loose adjustable bevel-faced clamps or sliding plates, P P, having notches O, by which they may be adjusted upon the uprights B B, between these and the churn-body, after the latter has been placed in position.

The churn-body is provided with a centrally-perforated cover, Q, for the stem R of the dasher, which may be of any suitable construction or configuration. A bearing is provided 55 for the said dasher-stem, between the transverse brace E and a plate, S, secured upon the face of the latter by means of brackets T and pins or keys U. The head I is provided with a vertical perforation to receive the upper end of 60 the dasher-stem, which is secured by a transverse pin or key V.

The spindles H of the head I are connected by a forked pitman, W, with a crank, X, formed upon a shaft, Y, mounted in the upper ends of 65 the uprights B B. Said shaft carries a fly-wheel, Z, and a pinion, A', engaging a gear-wheel, B', upon a shaft, C', mounted in suitable boxes upon the face of one of the uprights B, which is slotted, as shown, for the accommodation of the said gear-wheel. The shaft C' 70 has a handled crank, D', by which the machine may be operated.

From the foregoing description, taken in connection with the drawings hereto annexed, the 75 operation and advantages of my invention will be readily understood.

By removing the clamps P P, face-plate, S, and key V, the sliding platform L, with the churn-body, may be readily slid out of the way 80 of the operating mechanism, and by reversing this operation it may in a moment's time be adjusted ready for churning. The entire device is simple, convenient, and easily operated.

Having thus described my invention, I claim 85 and desire to secure by Letters Patent of the United States—

In a churn-motor, the combination, with suitable uprights, of a pair of adjustable clamps and a sliding recessed floor, all combined to 90 operate so as to hold the churn-body detachably, as herein described, for the purpose set forth.

In testimony that I claim the foregoing as my own I have hereto affixed my signature in 95 presence of two witnesses.

GEORGE W. FLOOD.

Witnesses:

D. E. McCCLURE,
EZEKIEL J. SHIRTS.
